UNITED STATES PATENT OFFICE

150,820

DESIGN FOR A LIGHT FIXTURE SUPPORT

Ernst G. Anderson, deceased, late of Chicago, Ill.,
by E. Harold Anderson, administrator, Lake Bluff, Ill., assignor to Simplet Electric Co., Chicago, Ill., a corporation of Illinois

Application July 8, 1946, Serial No. 131,369

Term of patent 14 years

(Cl. D26—1)

To all whom it may concern:

Be it known that Ernst G. Anderson, now deceased, late a citizen of the United States and a resident of Chicago, in the county of Cook and State of Illinois, and whose administrator is E.
Harold Anderson, residing at Lake Bluff, in the county of Lake, State of Illinois, has invented a new, original, and ornamental Design for Light Fixture Support, of which the following is a specification, reference being had to the accompanying drawing, forming part thereof in which:

Fig. 1 is a side perspective view, Fig. 2 is an end perspective view, Fig. 3 is a top plan view, and Fig. 4 is a bottom plan view of a light fixture support embodying the present new design.

What is claimed is:

The ornamental design for a light fixture support, substantially as shown.

E. HAROLD ANDERSON,
Administrator with the Will Annexed of the Estate of Ernst G. Anderson, Deceased.
